INDUCTION TIMING MOTOR

Application filed October 28, 1926. Serial No. 144,770.

My invention relates to induction timing motors used in demand attachments for induction watthour demand meters and more particularly to means for adjusting the intensity of electromagnetic flux in the field magnets thereof.

An object of my invention is to provide means for accurately adjusting the flux intensity of the electromagnetic fields of such instruments as those above specified.

Another object of my invention is to provide adjusting means, of the above indicated character, that shall be easily and simply made in field service.

It is necessary that the timing motors used in demand attachments for induction watthour meters shall rotate at a definite speed, since a predetermined number of revolutions of the disk of the motor determines the interval of time during which certain gears of the mechanism are maintained in engagement. Any deviation in the speed of the disk will cause a corresponding error in the demand register. Therefore, I provide means for adjusting the speed of the disk to insure the proper functioning of the demand-indicating device.

Such adjustment is affected by short-circuiting the magnetic pole elements of the energizing electromagnet by a magnetic-flux conductor, thereby adjusting the intensity of the electromagnetic field which influences the disk.

In the prior art, the intensity of the electromagnetic field has been adjusted by varying the quantity of current flowing in the coil of the electromagnet, by means of an adjustable resistor in series therewith. That method of adjustment was less accurate than the one herein described and had the further disadvantage of requiring the joint between the resistor and a tap conductor on the coil, to be resoldered every time an adjustment was made.

In practicing my invention, I provide an adjustable screw between poles of the electromagnet for partially short-circuiting the electromagnetic field which might influence the disk.

Figure 1 of the accompanying drawings, is

a front view, partially in elevation and partially in section, of an electromagnet structure for an instrument embodying my invention; and

Fig. 2 is a side elevational view of the electromagnet structure shown in Fig. 1.

A timing induction motor embodying my invention comprises, in general, a magnetizable core member 1, an armature 2, a potential winding 3, a secondary coil 17, a tertiary coil 4 and a screw 5.

The magnetizable core 1 is constructed of a plurality of laminations having a central portion 6 and side portions 7 and 8 that are integral with a base portion 9 at one end and spaced apart at their free ends by air-gaps 10 and 11. A slot 12 is provided near the free end of the central portion 6, and the side portions 7 and 8 are provided with laterally extending horns 13 and 14, respectively. The potential winding 3 is disposed around the central portion 6 in rectangular windows 15 and 16 in the side portions 7 and 8. A secondary coil 17 surrounds coil 3 in the rectangular windows 15 and 16 and is connected in series with the tertiary coil 4 and a resistor 19. The tertiary coil 4 is disposed around the free ends of portions 6 and 8 and in slot 12.

The armature 2 is mounted on a shaft 18 and is disposed adjacent the ends of portions 6, 7, and 8 in a plane parallel to their faces and separated therefrom by an air-gap.

The screw 5 bridges the air-gap 10 in suitable screw threads, located in the free ends of portions 6 and 7. When turned by means of a slot 20 in the head thereof, it serves to increase or decrease the length of the flux-shunting path between the lateral areas of the portions 6 and 7, thereby varying the effective flux that influences the disc.

When the winding 3 is operatively connected to an electric circuit (not shown), currents are induced in secondary coil 17 which flow through the tertiary coil 4, setting up lines of flux in the core member 1 that emanate from the free ends of the portions 6, 7, and 8, and traverse the disc or armature 2 to effect its actuation. A primary adjustment of the intensity of the electromagnetic field, to

secure a proper speed of the armature, is made by adjustment of resistor 19 which regulates the quantity of current to energize coil 4. This primary adjustment is then refined to a high degree of accuracy by varying the length 5 of the screw 5 in contact with the threads set in the lateral areas of portions 6 and 7. By thus varying the short-circuited flux to the proper quantity by means of the screw 5, the 10 speed of the armature 2 may be very accurately adjusted without affecting the torque on the armature appreciably.

The screw 5 provides a convenient means for accurately adjusting the strength of electromagnetic flux field which determines the 15 speed of the timing motor. A very accurate speed adjustment of the motor may thus be effected when the instrument is in service, by merely turning the screw 5 by means of a 20 simple tool, after the primary adjustment of the resistor 19 has been made.

While I have shown my invention in its preferred form, it will be understood that various modifications may be made without departing from the spirit and scope of the 25 invention as set forth in the appended claims.

I claim as my invention:

1. A timing motor of the induction-meter type comprising a three-legged core, the three 30 legs being joined at the back end and separated by gaps at the front end, the central leg having a slot in its front end forming two central half-poles, a single-phase exciting winding tending to give the front end of the 35 central leg a polarity substantially opposite to that of the front ends of the other legs, a de-phasing winding embracing the front end of one of the outer legs and one of the central half-poles, and a disk armature pivoted to ro- 40 tate with its face close to the front ends of said legs, characterized by a screw-adjusted magnetic-flux-varying means disposed in one of the gaps between the front end of the central leg and the front end of one of the side 45 legs.

2. A timing motor of the induction-meter type comprising a three-legged core, the three legs being joined at the back end and separated by gaps at the front end, the central 50 leg having a slot in its front end forming two central half-poles, a single-phase exciting winding disposed on the central leg at a point removed from its front end, a secondary winding disposed in transformer relation to the 55 exciting winding, a de-phasing winding embracing the front end of one of the outer legs and one of the central half-poles, a rheostat connecting the de-phasing winding to be energized from the secondary winding, and 60 a disk armature pivoted to rotate with its face close to the front ends of said legs, char- 65 acterized by a screw-adjusted magnetic-flux- varying means disposed in one of the gaps between the front end of the central leg and the front end of one of the side legs.

3. A timing motor of the induction-meter type comprising a three-legged core, the three legs being joined at the back end and separated by gaps at the front end, the central leg having a slot in its front end forming two central half-poles, a single-phase exciting winding tending to give the front end of the central leg a polarity substantially opposite to that of the front ends of the other legs, a de-phasing winding embracing the front 70 end of one of the outer legs and one of the central half-poles, and a disk armature pivoted to rotate with its face close to the front ends of said legs, characterized by a magnetizable screw fitted laterally and adjustably into the gap between the front end of the central leg and the other one of the outer legs.

4. A timing motor of the induction-meter type comprising a three-legged core, the three legs being joined at the back end and separated by gaps at the front end, the central leg having a slot in its front end forming two central half-poles, a single-phase exciting winding disposed on the central leg at a point removed from its front end, a secondary winding disposed in transformer relation to the exciting winding, a de-phasing winding embr- 80 acing the front end of one of the outer legs and one of the central half-poles, a rheo- 85 stat connecting the de-phasing winding to be energized from the secondary winding, and a disk armature pivoted to rotate with its face close to the front ends of said legs, characterized by a magnetizable screw fitted laterally and adjustably into the gap between the front end of the central leg and the other one of the outer legs.

In testimony whereof, I have hereunto sub- 90 scribed my name this 26th day of October, 1926.

ARGYLE R. RUTTER.
